UNITED STATES PATENT OFFICE.

GEORGE B. REED, OF CLEARFIELD, PENNSYLVANIA.

PLAYING CARD.

Application filed September 8, 1928. Serial No. 204,692.

This invention relates to games and toys, and more particularly to a playing card of the type employed when playing numerous games.

5 One object of the invention is to provide a card which is substantially of an oblong shape but of such marginal configuration that a pack of cards having the configuration shown may be easily held by a dealer and 10 thoroughly shuffled and dealt without danger of the edge portions of the cards becoming marred, during a shuffling and dealing operation.

Another object of the invention is to provide 15 a card of such configuration that its face may be ornamented by curved lines if so desired and thereby produce an attractive card.

The invention is illustrated in the accompanying drawing, wherein

Figure 1 is a face view of a card formed in accordance with this invention.

Figure 2 is a modified form of card.

The card shown in Figure 1 and indicated 25 in general by the numeral 1 is cut or stamped from thin sheet material such as thick paper, celluloid or any other desired material. The card may be of any desired length and width but is preferably substantially oblong in 30 shape and is provided with rounded corners 2, connecting its end edges 3 with or straight cut with its side edges 4. The end portions of the side edges extend straight and parallel to each other but their intermediate portions 35 are curved inwardly as shown at 5 thereby providing inwardly curved intermediate por-

tions which will cause a deck of cards to have side recesses in which the fingers of a hand holding the cards may be received. Therefore the edges of the cards are not liable to be 40 marred while holding a deck when dealing and also the edges will not be liable to be marred when shuffling a deck of cards.

The card shown in Figure 2 and indicated in general by the numeral 6 is in most respects similar to the card shown in Figure 1 and has its side portions formed with recesses 7 corresponding to the recesses 5. Instead of having its end edges cut straight as shown in Figure 1 this card has its end edges formed 50 with recesses 8 which are similar to the recesses 7 and serve to prevent the ends of the cards from having their edges marred in the same manner that the recesses 7 protect their side portions. These recesses not only serve 55 to protect the card but permit their faces to be ornamented by curved lines as previously set forth.

What is claimed is:—

A playing card substantially rectangular 60 in shape and having opposed side edges, the said side edges being formed with straight cut end portions of an appreciable length and intermediate portions curved inwardly from the end portions to provide a card having 65 wide end portions and an intermediate portion substantially reduced in width from its ends to increase flexibility of the card and permit a deck of such cards to be easily held and shuffled.

In testimony whereof I affix my signature.

GEORGE B. REED. [L. s.]
